C. CROW,

Lifting Jack,

N° 64,949,

Patented May 21, 1867.

Inventor
Charles CROW

United States Patent Office.

CHARLES CROW, OF ONARGO, ILLINOIS.

Letters Patent No. 64,949, dated May 21, 1867.

IMPROVEMENT IN LIFTING-JACKS.

The Schedule referred to in these Letters Patent and making part of the same.

TO ALL WHOM THIS MAY CONCERN:

Be it known that I, CHARLES CROW, of Onargo, in the county of Iroquois, and State of Illinois, have invented an Improved Lifting-Jack; and I do hereby declare that the following is a full, clear, and exact description thereof, reference being had to the accompanying drawings, and letters of reference marked thereon, in which—

Figure 1 is a perspective representation of my improved lifting-jack.

Figure 2 is a longitudinal sectional elevation of the same.

The object of my invention is to combine in one machine the windlass and rack, so that both may be operated in conjunction as a power for raising buildings of small dimensions made of wood, but more especially those resting on or near the ground, in which the water comes so near the surface that it is inconvenient to use the common jack-screw.

The nature consists in using a substantial frame in which operate one or more vertical racks, which may be raised or lowered by means of suitable cog-gearing. The sill or bottom of the house is made to rest on steps secured to the rack, which, when elevated, will raise the house. It consists further in the use of a chain or rope operating upon the shaft of the cog-wheels as a drum passing upward over a pulley, then downward and under the house, connecting with a similar chain operated by the same kind of jack on the opposite side of the house.

To enable others skilled in the art to make and use my invention, I will describe its construction and operation.

A represents the strong substantial frame, made of wood or other suitable material. B C show the vertical guides secured to the frame A which supports the racks D. These racks have the tongues m, which operate in the grooves U, made in the sides of the guides B C for the purpose of holding the racks in position when elevated by means of the gearing. F F are the girts which prevent the guides C from spreading apart, and n is the tie which supports the tops of the guides B C. S shows the shaft operating in bearings secured to the frame A, which supports the ratchet-wheel R, crank T, and cog-wheel P. V' shows the shaft supporting the cog-wheel o, which is also used as a drum for operating the rope or chain E. The opposite ends of the shafts are supported by that part of the frame shown at A'; and when two racks are used, as shown at fig. 1, it is necessary to use similar wheels to O P upon the shafts V' S at the proper place, so that both racks may be operated in conjunction. When it is required to raise heavy buildings two racks ought to be used, as the jack will stand more steady, and is not so liable to be strained. But for very small buildings a single rack, when using the rope and drum at the same time, is sufficient. Q represents the braces supporting the guides C, and may be made either straight or curved, as most convenient. I shows steps for supporting the building when elevating the same. I' represents mortises made in the racks C for the purpose of supporting steps similar to I when it is required to raise any body that is too high to be conveniently reached by the lower steps. J shows the common pulley over which the rope or chain E passes, as seen at fig. 2. This rope operates against the inner side of the roller H, which prevents the rope from being drawn out of place.

Operation.

The red lines Y represent a broken section of the house resting on the steps I and chain X, which is secured to the rope E at W. The chain X is supposed to pass under the house and connect with a rope operated by the jack placed on the opposite side of the house. After the jacks have been adjusted in this manner all that is required is to turn the crank T so as to elevate the rack the required distance. The number of jacks necessary for raising a house must depend upon its size and weight. The size of the drum V' is made so as to take up the rope precisely with the movement of the racks upward. J is the common pawl for holding the ratchet R.

I do not consider the rack and pinion a new device, they having been used for many years and various purposes; I therefore do not claim them. But the arrangement of the movable steps I is new, and when used in combination with the devices disclaimed provides means for raising buildings much higher than if single stationary steps were used. The rope and drum is also an old device, and for that reason is not claimed. But the arrangement of the roller H, pulley J, and drum V' is new and practical, as seen at fig. 2.

Having thus described my device, what I claim as my invention, is—

1. The arrangement and combination of the movable steps I, racks D, and guides B C, when constructed to operate substantially as and for the purpose set forth.

2. The combination of the roller H, rope E, pulley J, inner guides C, and drum V', when arranged substantially as and for the purpose described.

CHARLES CROW.
